UNITED STATES PATENT OFFICE.

JAMES G. NORTON, OF LEONIA, NEW JERSEY.

PAPER CONTAINER.

Application filed July 1, 1921. Serial No. 481,781.

This invention relates to paper containers, the illustrated container being particularly designed for use in dispensing ice cream.

It is an object of the invention to provide a container composed of paper or the like, which can be manufactured so cheaply that it may be discarded after a single use without appreciable economic loss and from which ice cream, syrup or fruits or any combination of them may be eaten with satisfaction to the user while he is walking, riding in a vehicle such as an automobile, or sitting, in the absence of a table or other dish support.

To this end an important feature of the invention resides in the provision of a paper container comprising a body portion adapted to receive a substance of human consumption such, for example, as ice cream and a member mounted on the body portion and constructed to facilitate the support of the container by the hand of the user. Preferably, the body portion of the container is substantially cone-shaped, and is provided at its smaller, lower end with a substantially cylindrical, tubular portion arranged to be held in the hand and having its lower end closed.

It is a further object of the invention to provide a container which is particularly well suited to the combined dispensing of ice cream and cake, and a further feature of the invention resides in the provision of a body member adapted to contain ice cream and a member extending outwardly from the body member and constructed to support a piece of cake.

The last-mentioned feature of the invention may be applied in various ways without departing from the spirit of the invention. At the present time, however, I prefer to make the body portion of the container in the form of a cone and to provide an extension or apron extending outwardly from the top part of the cone in a substantially horizontal plane. The apron is so shaped as to provide a safe support for the cake and at the same time to facilitate the eating of cake from it, and the upper edge of the body portion of the container is preferably turned in to prevent the contents of the container from slopping over.

Other objects and features of the invention will be apparent as the description proceeds

and will be pointed out in the appended claims.

In the drawings:

Fig. 1 is a view in perspective of the improved container on a reduced scale;

Fig. 2 is a plan view of the container;

Fig. 3 is a view of the container on the line 3—3 of Fig. 2;

Fig. 4 illustrates the manner in which the container blanks are formed;

Fig. 5 illustrates the manner of molding the blanks roughly into the shape of the containers;

Fig. 6 illustrates the manner of forming the container with turned upper edges;

Fig. 7 is a central, vertical section of the container with the apron omitted; and

Figs. 8 and 9 are views corresponding with Fig. 7 and showing the container in plan and perspective respectively.

As illustrated, the improved container comprises a conical body portion 2 adapted to contain ice cream and a substantially cylindrical, tubular portion 4 depending from the body portion, closed at its lower end as indicated at 5, and constructed to be engaged by the hand of the user and thus to render it easy for the user to support and manipulate the container while a substance of human consumption such, for example, as ice cream is being eaten from it.

The tubular handle portion 4 of the container preferably communicates at its upper end with the interior of the body portion 2, as shown in the drawings, in order to enable the containers to be packed in cartons in nested relations for convenience and economy in shipment and to cause them to take up but little space at a soda fountain or other place where ice cream is served. If the material from which the containers are made is very thin and flexible, they may be satisfactorily nested even if their tubular handle portions 4 are cylindrical. It is preferred, however, to taper the handle portions 4 of the containers inwardly from their upper ends to the tips of their lower ends, so as still further to facilitate the nesting of the containers. Manifestly, the degree of taper of the handle portions 4 may vary with the character of the material from which the containers are made, that is, the thinner and more flexible the ma-

terial, the less the degree of taper required to enable the containers to be properly nested.

A container shaped in the form of a cone from its upper to its lower end is not satisfactory for use in serving ice cream sundaes. One of the reasons why such a container is not satisfactory is that a cone, particularly, when it has a large degree of taper, gives a feeling of insecurity when held in the hand, for the 10 reason that it merely rests upon the partially shut hand without affording any part which can be grasped by the fingers. If an attempt is made to close the fingers about a cone, it is forced upwardly in the hand, and the result 15 of such effort is a less secure rather than a more secure hold.

In the illustrated embodiment of the invention, the longitudinal contour lines of the tubular handle portion 4 are arranged 20 at an angle of approximately 135° with the longitudinal contour lines of the body portion 2 of the container. The angular relation between the longitudinal contour lines of the body and handle portions of the container may vary considerably from 135° 25 within the scope of the invention, and such variation may be effected by changing the degree of taper of the handle portion or the body portion or both from that shown in 30 the drawing. The body portion of the container should, however, be formed with a considerable taper in order to provide a receiving portion of the usual and proper shape for containing a sundae, and the angle between 35 the longitudinal contour lines of the handle portion and those of the body portion should not exceed 150° in order to enable the handle portion to be grasped by the fingers as distinguished from a smooth cone 40 which cannot be so grasped.

The provision of the container with a handle portion and a body portion having their longitudinal contour lines at an angle of 135° to each other, as shown in the drawing, provides an annular channel about the container at right angles to its center line or axis, one side of the channel being defined 45 by the outer surface of the body portion 2 of the container, the other side of the channel being defined by the outer surface of the handle portion 4, and the deepest point of the channel being at the juncture of the handle and body portions. The channel thus formed receives the hand and greatly assists 50 in enabling the user to obtain a firm hold on the container while its contents are being eaten.

The container of this invention is constructed to be held with the hand in its 55 natural position, that is, with the lateral dimension of the palm of the hand arranged vertically and the fingers lying one above another. Moreover, the form of the improved container enables it to contain a sundae of the usual size and to be held, not only

with the hand in a natural position but with the fingers closed about the handle portion 4 of the container with no effort or strain. The fingers are merely relaxed about the handle portion 4, and the thumb rests upon 70 the end of the index finger, as appears from Fig. 2. The holding of the improved container involves no discomfort and does not detract in any degree from the enjoyment of the ice cream or other substance which is 75 eaten from the container.

Preferably, and as shown in the drawing, the contours of the handle portion 4 and the body portion 2 have single straight-line elements which meet in sharply defined angles 80 at the juncture of said portions. Manifestly, however, the longitudinal contour lines of the container may comprise a curve at the junction of the handle and the body portions with no sharply defined apex where said portions 85 are joined.

The handle portion 4 should be of a length at least one-half as great as the distance between the planes of the upper and lower ends of the body portion 2 or, in other words, as the 90 length of the axis of the body portion. I now prefer to make the handle portion 4 of a length less than the length of the axis of the body portion 2 but approximating more or less closely the length of the axis of the body portion, as clearly appears from the drawing. This construction enables the handle portion 95 4 to be engaged by at least two fingers of the user's hand, as is desirable.

Extending from the top part of the body portion 2 is an apron 6 adapted to support a piece of cake, a spoon for use in eating ice cream from the container, or both cake and a spoon. The main body of the apron 6 is disposed in a horizontal plane, and the apron is 100 preferably formed with a substantially straight edge 8 extending outwardly from the body 2 of the container and a curved edge 10 extending from the outer end of the straight edge 8 to the body portion 2. The straight edge 8 is arranged in the plane of the main body of the apron 6, but the curved edge of the apron is preferably turned upwardly as indicated at 12.

The container is designed to be held in the 115 hand as indicated by broken lines 14 in Fig. 2. It will be apparent, therefore, that a piece of cake such as is exhibited by full lines 16 on Fig. 1 or a spoon 17 will be safely held in position on the apron 6 by the upturned edge of the apron and that the cake may be eaten very conveniently from the straight edge 8.

The broken lines 18 on Fig. 2 indicate the sleeve of the person using the container. It 125 will be apparent from this view that the apron 6 acts also to protect the sleeve of the wearer from being soiled by the ice cream or other substance being eaten.

In order to prevent liquid such, for exam- 130

ple, as fruit syrup from being slopped from the container, the conical body portion 2 has its upper edge turned in as shown at 20 (Fig. 3).

5 The improved container may manifestly be made in various ways. A convenient and cheap method by which they may be manufactured consists in severing a piece of paper stock such as the piece 22 in Fig. 4 along the 10 curved line 24 and the straight line 26, and then molding the blank thus formed into the shape of the container.

The container blanks when severed from the stock comprise a circular portion 28 adapted to be formed into the body portion 2 and cylindrical portion 4 of the container and a second portion 30 which constitutes the apron 6 in the finished article. The line of juncture of the portions 28 and 30 is indicated in Fig. 20 4 by the broken line 32.

The molding operation may be performed by means of a lower mold 34 (Fig. 5) and an upper mold 36. The lower mold 34 is preferably formed with a substantially cylindrical 25 opening 37 corresponding to the desired shape of the portion 4 of the container and communicating at its upper end with a conical chamber 38 corresponding in contour with the desired contour of the body portion 2 of the 30 container. The lower mold 34 is also formed on its upper side with a recess 40 adapted to receive the apron-forming portion of the container blank.

The container blank is laid across the top 35 of the lower mold 34 with the portion 30 so disposed as to register with the recess 40 of the mold 34 when the blank is caused to enter the mold. The blank is thrust into the lower 0 mold 34 by the upper mold 36 which comprises a lower, cylindrical member 42 adapted to enter the opening 37 of the lower mold, a 5 conical portion 44 constructed to fit into the chamber 38 of the lower mold 34, and a laterally extending part 46 which is received in the recess 40 of the lower mold to impart the desired shape to the apron 6 of the container. In order to turn the curved edge 10 of the apron 6 upwardly the outer wall 48 of the recess 40 and the outer surface 50 of the part 0 46 are inclined upwardly as shown in Fig. 5.

The cylindrical member 42 of the upper mold 36 may be formed in two pieces between which is interposed a compression spring 52. This construction insures that the blank will 5 fully enter the mold before it is engaged by the conical portion 44 of the mold 36.

The blanks after they leave the mold 34 are preferably subjected to a second molding operation. In this operation a molding element 54 constructed to fit into the conical portion 2 and cylindrical portion 4 of the blank is first inserted into the blank and the element 54 and the blank are then interposed between a supporting member 56 and a top mold 58. The top part of the element 54 is

rounded inwardly at 60, and the inner surface of the mold 58 is correspondingly formed so that when the mold 58 and the element 54 are caused to approach each other, the upper edge of the conical portion 2 of the container 70 blank is turned inwardly as indicated at 62. In order to cause the upper edge of the container to be inturned at the portion adjacent to the apron 6, the apron 6 is supported during the second molding operation on a yielding member 64 and the top mold 58 is thickened at the point where it engages the apron 6 as shown at 66 (Fig. 6). The mold 58 and supporting member 64 engage the apron 6 at a point 68 spaced from the inner edge of the apron. With this construction, when the molding element 54 and top mold 58 are brought together, the paper between the points 68 and 70 (Fig. 6) is formed into an upwardly and inwardly extending fold as indicated in broken lines in Fig. 6.

The opening 37 of the mold 34 preferably tapers slightly from top to bottom in order that the cylindrical portions 4 of the containers will be somewhat larger at their upper ends than at their lower ends, thus enabling the containers to be nested for shipment. When the containers are nested and shipped their inturned upper ends 20 are forced outwardly but they return nearly if not quite to their original contour when they are again separated from each other.

If it is desired to make the containers of very thin paper, it may be necessary or desirable to enclose the cylindrical portions 4 of the containers in thimbles 72 of relatively thick paper or other similar material.

The illustrated container is designed to contain a paper cone 74 of the type commonly used in glass or metal holders at soda fountains for sanitary reasons. It will be manifest, however, that the invention is not limited to use with a cone of the type of the cone 74, and that the container of this invention may, if desired, be formed of paper or other material impermeable to liquid and adapted to receive the substance to be eaten without the use of any intermediate receptacle. Certain features of the invention, for example, a body portion adapted to contain a substance of human consumption and a member mounted on the body portion and constructed to be engaged by the hand to facilitate holding the container while the substance is being eaten from it, may be embodied in a container which is not provided with a shelf or apron and does not have a turned-in edge.

In the event that the improved container is used without a paper cone 74, the cream is 125 preferably pressed in somewhat as it is placed in the container. The cream may thus be caused to form a liquid-tight seal between itself and the walls of the container which enables syrup to be added to the container after 130

- insertion of the cream without the syrup being allowed to flow downwardly into the handle portion 4. When the cream has been nearly all eaten a small amount of it, together with a little of the syrup may drop into the handle portion. So long, however, as the cream does not melt, it will generally adhere to the walls of the cup. Accordingly, any material which finds its way into the handle portion 4 will be in the form of a thick, sticky liquid which may be readily recovered by tipping the container so as to cause it to flow out on the side of the cup from which it may be removed by a suitable spoon.
- 15 Although the container of this invention has been described as being made of paper, it is recognized that other materials may be used which possess qualities similar to paper such as cheapness, etc. The material used is not only cheap so as to enable the containers to be discarded after a single use without substantial economic loss, but is also preferably easily disintegrable by force so that, if desired any liquid which collects in the handle portion 4 may be recovered by tearing the body portion down to the handle portion or by breaking the handle portion from the body portion. The material must, however, be liquid-proof over a period of time long enough to enable its contents to be eaten with a spoon or other suitable implement without haste and with reasonable allowance for interruption plus a liberal factor of safety. The phrase, "period required for consumption of its contents", and like phrases appearing in some of the claims are intended to signify a period of time such as hereinbefore described. Cake dough of the kind heretofore used in ice cream cones, which have come to applicant's notice, is undesirable for use in making the containers of this invention, because it is not liquid-proof over a sufficiently long period. If, however, cake dough can be made sufficiently liquid-proof for the purposes of this invention, it is recognized that it may be used without departing from the principles of the invention. It is further of importance that the material from which the containers are made be easily disintegrable by water over an extended period of time, in order that containers which are thrown out of automobiles along the roadside will soon fall to pieces under the action of the weather.
- 55 Certain features of the invention including the construction and arrangement of the apron 6 may be embodied in containers composed of any desired material such, for example, as glass or silver.
- A serving of ice cream is indicated in Fig. 60 7 by broken lines, and syrup supplied with the ice cream is shown at B.
- It will also be noted by reference to the drawings that the length of the handle portion 4 is less than one-half of the diameter 65 of the larger end of the body portion 2. A handle portion of such length enables the container to be held in the hand with a feeling of security, since if the container tends to tip in the hand, it can be righted by pressure on the handle 4, which imparts to it a pivotal movement about the seat of the body portion 2 on the upper sides of the thumb and forefinger. The handle portion should be of the least length which will enable the container to be securely and comfortably held in the hand, since the capacity of such portion should be small, to the end that no considerable part of a serving of ice cream can be contained in it. The dimensions of the handle portion 4, as shown by applicant and recited in his claims, are, therefore, very important to the production of a practical container for use in serving ice cream sundaes.
- Having fully described the invention what is claimed is;
1. In a container, a substantially conical body portion adapted to contain ice cream, and a member extending from the top part of the body portion and formed to support a piece of cake.
  2. A paper container comprising a body portion adapted to contain ice cream and a member mounted on the body portion and arranged to support a piece of cake or a spoon.
  3. A paper container comprising a body portion adapted to contain a substance for human consumption, a member mounted on the body portion and formed to facilitate the support of the container by the hand while the substance is being eaten from it, and a member projecting outwardly from the upper part of the body portion and constructed to protect the clothing of the user.
  4. In a container composed of paper or the like, a substantially conical body portion constructed to contain a substance for human consumption and an apron extending outwardly from the top part of the body portion and constructed to overlie and protect the sleeve of the user.
  5. In a container, a conical body portion constructed to contain a substance for human consumption and an apron extending outwardly from the top part of the body portion, said apron being formed to present a substantially straight edge extending outwardly from the body portion and an edge extending from the outer end of the first-mentioned edge to the body portion of the container.
  6. In a container, a substantially conical portion adapted to contain a substance for human consumption and an apron projecting from the top part of the body portion, said apron being formed to present a substantially straight edge extending outwardly from the body portion and a curved edge converging gradually from the outer end of the straight edge to the body portion, said straight edge being formed substantially in the plane of

the apron and said curved edge being inclined upwardly and outwardly from the main body of the apron.

7. In a container constructed to be discarded after a single use without substantial economic loss, an outer section composed of easily destructible material and comprising a frusto-conical body portion open at both ends and a tubular handle portion opening into the body portion and extending downwardly from the reduced lower end thereof, said handle portion being constructed so as to enable a number of said outer sections to be nested one within another and an inner 15 conical portion also composed of easily destructible material and constructed to fit into the body portion of the outer section and to close the lower end of the outer section.

8. A paper container comprising a substantially frusto-conical body portion adapted to contain a substance for human consumption and to be held with its large end upwards and a more nearly cylindrical, tubular, handle portion depending from the body portion in 25 position to be engaged by the hand in supporting the container, said tubular handle portion communicating at its upper end with the interior of the body portion so as to enable the containers to be nested and having its 30 lower end closed to prevent the escape of material from the container.

9. A container composed of material which is liquid-proof over a period of time required for human consumption of its contents by a 35 suitable implement but easily disintegrable by water over an extended period of time or by force, and comprising a substantially frusto-conical body portion adapted to contain a substance to be eaten and a tubular 40 handle portion depending from the smaller end of the body portion and opening into the body portion, said handle portion having its lower end closed and being constructed so as to enable the containers to be nested one within another and said handle and body portions being of the same order of axial length and forming an annular channel to receive the hand of the user.

10. A non-edible container composed of 50 material which is liquid-proof over a period of time required for the consumption of an ice cream sundae from it by a suitable implement and easily disintegrable by water over an extended period of time or by force, and comprising a substantially frusto-conical body portion adapted to contain a substance to be eaten, a tubular handle portion extending downwardly from the smaller end of the body portion and opening thereinto to permit nesting of the containers, and means for preventing escape of the substance through the bottom of the container.

11. A container composed of easily disintegrable material and comprising an upwardly and outwardly sloping body portion

adapted to contain a substance for human consumption and a tubular handle portion depending from the small end of the body portion and opening thereinto to permit nesting of the containers, said handle portion being of 70 a length such as to enable the user to obtain a firm hold on the container while the substance is being eaten from it, but not substantially exceeding the axial length of the frusto-conical portion so as to have a small capacity, and 75 means for preventing escape of the substance through the bottom of the container.

12. A container composed of easily disintegrable material and comprising a substantially frusto-conical body portion adapted to 80 contain a substance for human consumption and a tubular handle portion depending from the smaller end of the body portion and communicating at its upper end with the interior of the body portion, said handle portion having its lower end closed and being arranged to form with the body portion an annular channel lying in a plane substantially at right angles with the axis of the container with its deepest point not higher than the mid-point 85 of said axis and adapted to receive the hand to enable the user to obtain a firm hold on the container while the substance is being eaten from it.

13. A container composed of material 90 which is liquid-proof over a period of time required for human consumption of its contents by a suitable implement but easily disintegrable by water over an extended period of time or by force, and comprising a substantially 100 frusto-conical body portion adapted to contain a substance of human consumption and a tubular handle portion depending from the smaller end of the body portion, said body portion being open into the handle portion 105 and said handle portion being constructed so as to enable the containers to be nested one within another.

14. A paper container comprising a substantially frusto-conical body portion adapted to contain a substance for human consumption and a tubular handle portion opening into the body portion and depending from the smaller end thereof, said handle portion also being tapered downwardly and inwardly to 110 the tip of its lower end so as to enable the containers to be nested, and means for preventing escape of the substance through the bottom of the container.

15. A container composed of material 120 which is liquid-proof over a period of time required for human consumption of its contents by a suitable implement but easily disintegrable by water over an extended period of time or by force, and comprising an upwardly 125 and outwardly sloping body portion adapted to contain a substance for human consumption and a tubular handle portion closed at its lower end and depending from the smaller end of the body portion, said body portion be- 130

ing open into the handle portion and said handle portion being constructed so as to enable the containers to be nested one within another.

5 16. A container composed of material which is liquid-proof over a period of time required for human consumption of its contents by a suitable implement but easily disintegrable by water over an extended period of
10 time or by force, and comprising an upwardly and outwardly sloping body portion adapted to contain a substance for human consumption and a tubular handle portion opening into the body portion and depending from the smaller
15 end thereof, said handle portion being closed at its lower end and being tapered downwardly and inwardly to the tip of its lower end so as to enable the containers to be nested.

17. In a container constructed to be discarded after a single use without substantial 20 economic loss, an inner section composed of thin, flexible paper and formed in the shape of a cone, and an outer section composed of relatively thick, stiff paper and comprising 25 a main body portion shaped to conform to the inner section and a tubular, handle portion opening into the body portion and extending downwardly from the reduced lower end thereof, said handle portion being constructed so as to enable a number of said outer sections 30 to be nested one within another, and said inner section being constructed to fit into the body portion of the outer section and to close the lower end of said outer section.

In testimony whereof I affix my signature.
JAMES G. NORTON.
